H. K. SANDELL,
APPARATUS FOR RAISING THE TONE ARMS OF SOUND REPRODUCING DEVICES.
APPLICATION FILED APR. 2, 1919.

1,331,215.

Patented Feb. 17, 1920.

UNITED STATES PATENT OFFICE.

HENRY K. SANDELL, OF CHICAGO, ILLINOIS, ASSIGNOR TO HERBERT S. MILLS, OF CHICAGO, ILLINOIS.

APPARATUS FOR RAISING THE TONE-ARMS OF SOUND-REPRODUCING DEVICES.

1,331,215.

Specification of Letters Patent. Patented Feb. 17, 1920.

Application filed April 2, 1919. Serial No. 286,825.

To all whom it may concern:

Be it known that I, HENRY K. SANDELL, a citizen of the United States, residing at Chicago, in the county of Cook and State of Illinois, have invented a new and useful Improvement in Apparatus for Raising the Tone-Arms of Sound-Reproducing Devices, of which the following is a specification.

This invention relates to devices for raising the tone arm of a phonograph or sound reproducing device, and more particularly to a device which operates automatically to raise such a tone arm when the latter reaches a determined point in its movement.

For the purpose of illustrating my invention and of fully and clearly describing same, I have illustrated an embodiment thereof in the accompanying drawings, wherein my invention is shown as applied to a horizontally floating tone arm of a sound reproducing device, said tone arm being capable of a vertical pivotal movement upon its support. The tone arm as illustrated is of the type more fully described in my prior application, Serial No. 246,447, filed July 24th, 1918. In the drawings—

Figure 1 is a side elevation of the tone arm illustrating the relative arrangement of the tone arm and the parts of the lifting device just prior to the operation of the latter.

Fig. 2 is a side elevation of a portion of the tone arm, illustrating the relative position of the tone arm and the lifting device 35 after the latter has been caused to operate.

Fig. 3 is a section through the pivotal portion of the tone arm support, the tone arm proper being removed from the portion of the support to which it is connected in normal use of the device.

In the device as illustrated 5 represents the supporting table of a sound reproducing device, or phonograph, from which rises a hollow base member or support 6, through 45 which the sound conduit passes. Upon this base member 6 is rotatably mounted a conduit member 7 which terminates in a head 8. Upon head 8 is mounted for a limited rotative movement relative thereto a socket 9, 50 which is likewise extended in a conduit member 10, on which the tone arm 11 is mounted, said tone arm 11 preferably having a rotative movement of 90° with relation to the conduit 10 and their common axis. 55 This tone arm 11 carries, as illustrated, a

sound box 12 and a suitable stylus holder 13 at its farther end. The conduit member 7 is so mounted on the base or support 6 that the entire tone arm may move freely in the horizontal direction. The head and socket members 8 and 9 together form a conduit joint which permits the tone arm 11 to be raised and lowered in the vertical direction at will. As regards the relative movements of members 8 and 9, the head 8 is fixed and the 65 socket 9 rotatable on their common axis.

As illustrated in the present embodiment of my invention I may provide a relatively fixed arm 14 and an independently movable lever member 15, the latter being provided 70 with means such as the elongated pin 16 for engaging the tone arm. I prefer to attach these elements to the conduit joint in such manner that they partake of the rotative movement of the conduit in the horizontal 75 plane and retain their positions relative to the tone arm during such movement. In the present embodiment of my invention I have illustrated the fixed arm 14 as rigidly secured to the head member 8 of the conduit 80 joint, being firmly held thereagainst by the shoulder or hub portion 17 of the screw 18, a suitable washer 19, likewise rigidly secured to the head member 8, being interposed between the fixed plate member 14 and the 85 head 8. The lever 15 is independently rotatable on the hub portion 17 of the screw 18.

The outwardly extending portion of the arm 14 is offset to provide a space between it and the lever 15 in which the means for 90 effecting the lifting movement of the lever 15 at the desired moment may be placed. As illustrated, this means may consist of an expanding U-shaped spring 20, the ends of which terminate in eyes or loops by which 95 the spring is attached to pins 21 and 22 on arm 14 and lever 15 respectively. To limit its movement relative to the fixed arm 14, the lever 15 is provided with transversely extending lugs 23 and 24, which are adapted 100 to engage the member 14 and thereby limit the movement of the lever 15 relative thereto.

In normal playing position, the tone arm 11 moves freely in a horizontal direction 105 about the pivotal axis of the conduit members 8 and 9, being supported by the stylus which rests upon the record 25. The normal position of elements 14 and 15, when the tone arm is in playing position is, as illus. 110

trated in Fig. 1, with the pins 21 and 22, to which the ends of the U-shaped spring 20 are attached, in such relative position with each other and with the pivotal center 5 of the lever 15 that the pin 22 on the lever 15 is on or below the line joining the pin 21 and the pivotal center of the lever. In this position the ends of the spring 20 are compressed together and the force or thrust exerted in its effort to expand is not productive of any relative movement of the two elements 14 and 15. It is apparent, however, that if by a suitable means the lever 15 were brought into such a relative position 10 that the pin 22 were raised above the line joining the pin 21 and the pivotal center of the lever, the force or thrust of the spring tending to expand would tend to raise the lever 15. In its upward movement 15 the lever 15 will, by means of pin 16, engage with the tone arm and raise the tone arm also. Furthermore, on then moving the lever 15 downward to such position that the pin 22 is again in line with or below the line joining the pivotal center and the pin 21 on arm 14, the lug 23 limiting the downward movement of the lever 15, the parts 20 will again lock themselves in the position 25 shown in Fig. 1.

30 To effect the initial upward and downward movement of the lever 15 at the predetermined points in the travel of the tone arm, the lever 15 is provided with a downwardly extending lug or finger 26, which 35 travels along an arcuate segment 27 attached to the supporting member 6, this arcuate segment 27 being provided at predetermined points with projecting lugs or pins 28 and 29. The position of these pins is 40 such that when the tone arm 11 reaches a predetermined point in its movement toward the center of the record 25, the finger 26 on lever 15 engages pin 28 and the lever is accordingly slightly raised thereby; and 45 the position of pin 29 is such that when tone arm 11 is moved outwardly from the center of the record to a predetermined point, the finger 26 is engaged thereby and the lever 15 moved downwardly. The latter downward 50 movement of the lever is assisted by the downward movement of the tone arm in placing the stylus attached thereto in playing position on the record.

It is apparent from the above construction 55 that, although the spring used has sufficient expansive force to raise the lever 15 and with it the entire tone arm 11, the force required to initiate the movement of the lever and to bring it into a position wherein the 60 full force of the spring may act is very slight.

Although I have illustrated and described in the present specification one embodiment

of my invention, it is clearly apparent that I am not limited to the specific construction 65 described therein, except in so far as such limitations are included in the accompanying claims:

1. In combination, a movable tone arm, a horizontal pivotal support therefor, an arm 70 mounted on said support and fixed against vertical movement, a vertically movable arm mounted on the support and provided with means adapted to engage the tone arm, a contracted U-shaped spring engaging the 75 fixed and movable arms and normally exerting its force to retain the movable arm out of engagement with the tone arm and means for bringing the movable arm into position such that the spring will exert its force to 80 cause the said movable arm to engage the tone arm at a predetermined point in the movement of the tone arm.

2. In combination, a tone arm, a horizontal pivotal support therefor, said support 85 and tone arm being oscillatable in a horizontal plane, a relatively movable arm attached to said support and provided with means for engaging the tone arm to raise the same, a relatively fixed arm attached to said support, an expanding spring normally engaging the fixed and movable arms in such manner that the latter does not engage the tone arm, and means operative at a predetermined point in the horizontal movement of 90 the tone arm to bring the movable arm into a position such that the spring forces the movable arm upward to engage and raise the tone arm.

3. In combination with a horizontally 100 movable tone arm, an upwardly movable member adapted to engage and raise the tone arm, a relatively fixed support, a spring mounted on said support and said movable member and exerting an expansive force on 105 the latter, the latter being normally retained in its lowermost position, and means operative when the tone arm reaches a determined position to bring the movable member into such position as to cause the spring to raise 110 it and the tone arm.

4. In means adapted to raise a horizontally 115 movable tone arm, a fixed support, a pivoted arm provided with means for engaging and lifting the tone arm, a spring 120 mounted on said support and exerting a thrust on the pivoted arm at a point on or below the line joining the point of support of the spring and the pivot of the arm, and means operative at a determined point in 125 the movement of said arm to raise the point of thrust of the spring above said line; whereupon the thrust of the spring is exerted to raise said arm and thereby to engage and raise the tone arm.

HENRY K. SANDELL.
